UNITED STATES PATENT OFFICE.

CHARLES L. LEDIN, OF STAMFORD, CONNECTICUT, ASSIGNOR TO THE YALE & TOWNE MANUFACTURING COMPANY, OF STAMFORD, CONNECTICUT.

DESIGN FOR A PADLOCK.

41,328.

Specification for Design.

Patented Apr. 25, 1911.

Application filed December 10, 1908. Serial No. 466,914. Term of patent 7 years.

To all whom it may concern:

Be it known that I, CHARLES L. LEDIN, a citizen of the United States, residing at Stamford, in the county of Fairfield and State of Connecticut, have invented a new, original, and ornamental Design for Padlocks, of which the following is a specification, reference being had to the accompanying drawings, forming a part thereof.

Figures 1 and 2 are views in front and

rear elevation of a padlock, showing my new design.

I claim:

The ornamental design for a padlock, as shown.

CHARLES L. LEDIN.

Witnesses:

FRANK M. FAWCETT,
EWART WESSON.
